The ornamental design for a mat for measuring foot size, as shown and described.

DESCRIPTION

FIG. 1 is a front elevational view of a mat for measuring foot size showing our new design;

FIG. 2 is a rear elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The broken lines depict portions of the mat for measuring foot size that form no part of the claimed design. The shadings in FIG. 1 represent planar surfaces. The surface on the mat in FIG. 1 has no depth.
